CLAIM

I claim the ornamental design for a scissors, as shown and described.

DESCRIPTION

FIG. 1 is a perspective view of the scissors in use with the hand of the user shown in phantom;

FIG. 2 is a front end view of the scissors;

FIG. 3 is a back end view thereof;

FIG. 4 is a right side view thereof;

FIG. 5 is a left side view thereof;

FIG. 6 is a top plan view thereof; and,

FIG. 7 is a bottom plan view thereof.

The broken line showing of the hand in FIG. 1 is for illustrative purposes only and forms no part of the claimed design.
